US0D1072252S

(12) **United States Design Patent** (10) **Patent No.:** **US D1,072,252 S**
(45) **Date of Patent:** **** Apr. 22, 2025**

(54) **DISSOLVABLE MEDICAMENT IMPLANT**

(71) Applicant: **AERIE PHARMACEUTICALS, INC.**, Bedminster, NJ (US)

(72) Inventors: **Thomas A. Shepard**, Rolesville, NC (US); **Tyler Pegoraro**, Raleigh, NC (US); **Leo Anthony Trevino**, Hurdle Mills, NC (US)

(73) Assignee: **ALCON INC.**, Fribourg (CH)

(**) Term: **15 Years**

(21) Appl. No.: **29/810,410**

(22) Filed: **Oct. 5, 2021**

(51) **LOC (15) Cl.** **24-03**

(57) **CLAIM**

The ornamental design for a dissolvable medicament implant as shown and described.

DESCRIPTION

FIG. 1 is a perspective view of the front and right of and above the dissolvable medicament implant;

FIG. 2 is a right side elevation thereof;

FIG. 3 a back plan view thereof;

FIG. 4 a front plan view thereof; and,

FIG. 5 is a top plan view thereof.

The left side elevation view of the dissolvable medicament implant is identical to the right side elevation view shown in FIG. 2 and the bottom plan view is identical to the top plan view shown in FIG. 5.

1 Claim, 2 Drawing Sheets
